UNITED STATES PATENT OFFICE

112,431

DESIGN FOR AN ASHTRAY

Jack Bierman, Chicago, Ill.

Application September 26, 1938, Serial No. 80,101

Term of patent 14 years

To all whom it may concern:

Be it known that I, Jack Bierman, a citizen of the United States of America and a resident of Chicago, Cook County, Illinois, have invented a new, original, and ornamental Design for an Ashtray, of which the following is a specification, reference being had to the accompanying drawing, forming a part thereof.

I claim:

The ornamental design for an ashtray, substantially as shown.

JACK BIERMAN.
